LEVER ACTUATED TUBE BENDING
HAND TOOL

Arthur J. Shiley, Philadelphia, Pa.

Application October 29, 1948, Serial No. 57,178

2 Claims. (Cl. 81—15)

1

My invention relates to a new and useful metal tubing bender and has for one of its objects to provide a device of this character especially adapted for bending hard metal tubing, particularly hard copper tubing. Because of the difficulty usually attending the bending of hard copper tubing and the cracking, rupture, splitting or malformations often resulting from the bending operations it has been the general practice to secure elbows of various shapes, nipples and the like, to the ends of adjoining lengths of straight tubing sections. By the use of my bending machine or device, the above mentioned extra parts and the work necessary for making the joints can be dispensed with and the possibility of many leaks eliminated.

Another object of this invention is to provide an exceedingly simple and effective device of the character mentioned which also will be compact and relatively light in weight whereby it may be readily carried in a mechanic's tool kit and used on the job for bending hard metal tubing.

Another object of the present invention is to construct a tubing bender including an eccentric channeled segment die carried by a frame having a handle and a foot-piece detachably connected thereto and a grooved roller movable in a true card of a circle in proximity to the channeled die about the outer curvature of the latter by a handle which projects across the first mentioned handle when the parts are in a neutral position or at the beginning of the bending operations.

A further object of the invention is to provide a unique means for taking up any sidewise stress on the operating handle to prevent damage to the several parts during a bending operation.

A still further object of the invention is to provide a simple and effective clamp for holding the tubing in the segmental die.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawing, in which:

Fig. 1 is a side view of the lever actuated tube bending hand tool with parts of the handles and foot-piece broken off and showing the elements in one position in elevation and illustrat-

ing some of them in other positions in dotted lines.

Fig. 2 is an edge view thereof looking towards the bottom of Fig. 1 and the handles and foot-piece removed.

Fig. 3 is an end view of the same looking towards the left hand side of Fig. 1 and the handles in a separated position at the completion of a bending operation.

Fig. 4 is an enlarged fragmentary sectional elevation on the line 4—4 of Fig. 1.

Fig. 5 is a similar view on the line 5—5 of Fig. 1.

In carrying out my invention as herein embodied 10 represents a bar or standard, preferably having a flat intermediate portion, with threaded sockets 11 and 12 at opposite ends. A part or section 13 of said intermediate portion is oblique to the end of the bar so that said ends or the sockets 11 and 12 are offset to one another and lie in different horizontal planes as shown in Fig. 1.

A grooved segmental bending die 14 is secured at one side thereof, where there is a web 15, Figs. 1 and 5, to the oblique portion 13 of the bar 10, by means of a fastening device 16, such as a rivet, and/or welding, leaving the major portion of said bending die 14 overhanging the axis of the socket end 12. The attached side or end of the bending die 14 has a lug 17, Fig. 4, projecting therefrom which engages the outer edge of the oblique or angular portion 13 of the bar 10 to further assist in holding the die and bar together in proper relation.

An axle 18, which may be a bolt, is projected through an enlarged portion or hub 19 of the bending die 14 and the bar 10. On the rear end of said axle 18, so as to be outside of and contiguous to the bar 13, is pivotally mounted a flat lever 20 provided with a threaded socket 21 at its outer free end.

On the lever 20 is a trunnion 22 in spaced alignment with the periphery of the bending die. On the trunnion is rotatably mounted a grooved roller 23 for coaction with the bending die when a workpiece is placed in the latter. Said roller is held on the trunnion and the outer free end of said trunnion is supported by a bracket 24 having one end engaged with said trunnion and the opposite end fixed to the lever 20 some distance beyond the trunnion. Because of the eccentric formation of the grooved portion of the bending die, when the lever 20 is adjacent the bar 10 the roller is spaced farther from the perimeter of said bending die than when the lever is moved away from said bar.

In other words, as the lever is actuated for a bending operation the roller gradually approaches closer to the bending die.

A latch 25 is pivoted at one end to axle 18 adjacent the front face of the bending die 14 or on that side of said die opposite the location of the bar 10 and lever 20. The other or free end of said latch is provided with a transverse notch 26 with its open end facing a direction opposed to the path of travel of the lever 20 as the latter is moved outwardly or away from the bar 10 as during a bending operation. This latch 25 is adapted to be detachably connected to the outer end of the trunnion, outside of the bracket 24 and when in engagement with said trunnion ties together the shaft 18, said latch 25, the trunnion 22, the bracket 24 and the lever 20 and functions to bias any sidewise stresses upon said lever 20 and thereby prevent bending thereof.

At one side of the bar 10, between the oblique portion 13 and the socket 11 are a pair of spaced ears 27 and 28, the former projecting from a face of said bar, to which it may be welded, and the latter lying against the outer edge of said bar 10 and having an offset 29 which extends around onto the face of the bar 10 opposite to the one from which the ears project. The ear 28 and its offset 29 are welded to the bar 10.

Between the ears is pivoted the shank 33 of the swinging clamp 31 which also includes the enlarged clamping foot 32 having a transversely beveled underneath surface 33. The swinging clamp is mounted on the pivot 34 fixed in the ears whereby said clamp oscillates laterally relative to the bending die across the perimeter of grooved circumference adjacent the rear end thereof to clamp tubing in said bending die.

In the socket 12 is screwed a foot-piece 35 which may be a short section of pipe or a nipple, such as found among the pipe fittings used by plumbers and pipe fitters, and handles 36 and 37, probably sections of pipe, are screwed into the 11 and 21, respectively.

In practice, the foot-piece 35 and the handles 36 and 37 are removed from their respective sockets when the device is to be transported or stored and the several components then can be packed to occupy a small space, such as a workman's kit. When the apparatus is to be used for bending metal tubing, especially hard copper tubing, the foot-piece and handles are assembled and said foot-piece mounted in a vise or equivalent holder or the terminal end of said foot-piece engaged upon a surface, such as a floor, with the tool in an inclined position. To place a section of tubing in the bending die, the lever 20 is moved into the starting location adjacent that part of the bar 10 provided with the handle socket 11, as shown in Fig. 1, the latch 25 is thrown back, as indicated by dotted lines, and the clamp 31 swung outward. This provides ready access to the grooved circumference of the bending die 14 and permits a length of tubing to be placed in said bending die and adjusted properly for location of the bend desired. With the tubing in position, the clamp 31 is swung into clamping position and the latch 25 is caused to engage the trunnion 22. By grasping the handles and moving the lever 20 away from the bar 10, the roller 23 will gradually approach the perimeter of the bending die as said roller moves in the arc of a true circle just outside of the circumference of the bending die, which is eccentric to shaft 18, thus smoothly forcing the tubing to assume the curvature of any desired portion of

said bending die. As the open end of the notch 26 in the latch 25 is opposed to the direction of travel of the lever 20 during the bending operation, said latch cannot, under ordinary conditions, become disengaged from the trunnion, at least until the lever movement is reversed. During the time the latch is in engagement with the trunnion said latch acts as a tie strap and will reduce to a minimum the likelihood of the lever being bent sidewise out of proper alignment.

Upon completion of the bending operation, the lever 20 is moved back to its normal position adjacent the bar 10, which may leave the latch 25 behind it, otherwise, said latch is moved away from the trunnion 22 and the clamp 31 is swung outward thereby removing all obstructions to the ready and easy release of the work.

Of course I do not wish to be limited to the exact details of construction herein shown and described as these may be varied within the scope of the appended claims without departing from the spirit of my invention.

Having described my invention, what I claim as new and useful is:

1. In a device of the kind described, a substantially flat bar having angularly offset end portions provided with sockets extending in parallel and opposite directions, one of said sockets constituting a foot socket and the other a handle socket, a segmental bending die having a groove in and extending throughout its perimeter, said bending die having one end imposed on one face of the bar and overhanging the projected axis of the foot socket, means to secure said bending die to said bar, a flat lever imposed on the face of said bar opposite the bending die, an axle projected through the bending die, bar and lever in the extended axis of the foot socket for pivoting said lever, the outer free end of said lever curved towards and crossing an imaginary extension of the handle socket of the bar when said lever is adjacent and substantially parallel to the handle end of said bar, a socket on the outer end of said lever, the perimeter of said bending die being eccentric to said axle, a trunnion on the lever spaced from the bending die and projecting from the inner face of said lever to overlie the perimeter of said bending die, a grooved roller journalled on said trunnion to cooperatively gradually approach the perimeter of the bending die as the lever is moved away from the bar, means to clamp tubing in the bending die at the secured end thereof, a foot-piece removably mounted in the foot socket, and handles removably mounted in the other sockets.

2. A metal tubing bender comprising a bar, foot and handle sockets at opposite ends of said bar to receive pipe sections to function as a foot-piece and handle respectively, a segmental bending die secured at one of its ends to said bar intermediate the locations of the sockets, said die having a groove along its perimeter, a lever, means to pivot one end of the lever to the bending die, the opposite free end of said lever curved inwardly towards the bar and projecting beyond the axis of the handle socket outside of the end of the latter when said lever is in the starting position of a bending operation, a socket on the face end of the lever to receive a pipe section acting as a second handle, a grooved roller mounted on said lever in opposed relationship to the groove of said bending die, a pair of ears projecting from the bar in a direction to overlie the perimeter of the bending die where the latter is secured to said bar, and a clamping member

including a shank pivoted between said ears and a foot for lateral swinging movements relative to the perimeter of the bending die and normally adjacent and just outside of said perimeter to clamp tubing in the groove of said bending die, said foot having a transversely beveled inner surface.

ARTHUR J. SHILEY.
